UNITED STATES PATENT OFFICE.

CARL V. DODGE, OF BELLEVUE, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

APPARATUS FOR RESHAPING ANNEALING BOXES.

Application filed August 13, 1925. Serial No. 50,009.

The present invention relates broadly to the art of metal bending and shaping, and more particularly to an apparatus particularly adapted for the reshaping of annealing boxes.

At the present time annealing boxes are very extensively utilized in the manufacture of sheets, and efforts have been directed with more or less success to the construction of annealing boxes in such manner as to prevent distortion of the walls thereof. Ordinarily, annealing boxes are sold on a pound basis, and as large annealing boxes weigh many thousand pounds, it will be apparent that any means for effecting an increase in the length of life of the annealing boxes represents a corresponding decrease in the relative cost of sheets produced by their use.

The present invention has particularly for its object the provision of an effective apparatus by means of which annealing boxes which have become distorted in use may be quickly and effectively restored to substantially their original condition, whereby they may again be put into service and again used.

In the accompanying drawings there is shown, for purposes of illustration only, a preferred embodiment of the present invention, it being understood that the drawings do not define the limits of my invention, as changes in the construction and operation disclosed therein may be made without departing either from the spirit of the invention or the scope of my broader claims.

In the drawings:

Figure 1 is a top plan view of an apparatus constructed in accordance with the present invention;

Figure 2 is a side elevation of the apparatus illustrated in Figure 1;

Figure 3 is a transverse sectional view on the line III—III of Figure 1;

Figure 4 is a horizontal sectional view on the line IV—IV of Figure 2; and

Figure 5 is a vertical transverse sectional view on the line V—V of Figure 4.

In accordance with the present invention, a straightening apparatus effective for restoring annealing boxes to the desired shape may comprise a base 2 on which the various operating parts of the apparatus are supported and on which is adapted to be carried the

annealing box B to be operated upon. This base may conveniently comprise side girders 3 fabricated from I-beams if desired and connected by transversely extending braces 4.

Adjacent one end of the base there is provided a motor 5, the shaft 6 of which may be connected to a pump 7 through a flexible coupling 8 diagrammatically illustrated in the drawings. The pump may be of any desired construction, having an intake connection 9 and an outlet connection 10. The inlet connection may cooperate at its lower end with a fluid reservoir R and at its upper end with the intake of the pump, while the outlet extends from the pump to a fitting 11. This fitting may comprise a cross, as illustrated in Figure 1, having a connection for a pressure gauge 12, a connection for a by-pass 13 and a connection for a pressure line 14, in addition to the connection for the outlet line 10. The by-pass 13 is provided with a controlling valve 15 which controls the flow through the by-pass to the fluid reservoir R.

With this construction it will be apparent that with the valve 15 in open position, fluid may be pumped from the reservoir R into the connection 11 and thence by the by-pass directly to the reservoir. With the valve 15 in closed position, however, fluid under pressure will be delivered to the pressure line 14 which is connected at its opposite end to a nipple 16 delivering to the interior of a cylinder 17 formed within the cylinder casting 18. This cylinder casting, as clearly illustrated in Figure 5, may have supporting projections 19 adapted to directly cooperate with the beams 3 to which they may be secured in any desired manner and in any desired adjusted position.

Cooperating with the cylinder is a piston 20 having a suitable packing 21 and carrying at its outer end a straightening head 22. This straightening head is guided by bolts 23 positioned in recesses 24 in the cylinder casting and surrounded by primary compression springs 25 and secondary compression springs 26. Conveniently, the primary and secondary compression springs at each side of the cylinder are adapted to be partially nested, this being accomplished by providing an intermediate spring housing 27 having a

flange 28 cooperating with one end of its associated primary compression spring and its opposite end turned inwardly to support one end of its associated secondary compression spring. The opposite end of either secondary compression spring may abut against a washer 29 held in place by a head 30 on a bolt 23. The threaded end of the bolt may be effectively protected and the desired compression initially secured on the springs by providing a nut 31 having a tubular projection 32 provided with an inner threaded portion 33 cooperating with the bolt. This tubular projection serves as a guide for the inner end 15 of the spring housing 27 and also as a guiding means for the bolt at the point of projection through the cylinder casting. In actual operation the load on the springs will preferably be adjusted initially in such manner 20 as to insure the return of the piston to the full line position illustrated in Figures 1, 2 and 4 of the drawings, it being apparent that movement in the opposite direction is obtained by the fluid under pressure supplied 25 to the cylinder to the pressure line 14.

The cylinder casting is of such construction that it is adapted to be built up to different sizes by the addition thereto of removable and replaceable unit sections 34, each unit 30 section having side openings 35 adapted to receive tie bolts 36 extending through openings 37 in the cylinder casting for maintaining the desired number of unit sections in applied position.

35 The straightening head 22 is conveniently curved at its outer end, as clearly illustrated in the drawings, whereby it has a limited area of contact with the portion of the wall of the annealing box B to be straightened. The 40 unit sections 34, on the other hand, are so shaped as to cooperate with a much greater area of the annealing box to thereby form a backing-up support for the apparatus during the projection of the piston and straightening head. By providing inwardly supporting zones in this or some similar manner, the straightening effect can be concentrated on that portion of the box requiring a straightening operation. When the straightening 45 has been accomplished to the desired extent, the valve 15 may be moved to open position, whereupon the spring means provided will be effective for emptying the cylinder of the fluid supplied thereto, returning the fluid to the reservoir R and restoring the straightening head to its normal position.

50 It will be apparent to those skilled in the art that the pump 7 may be provided with a suitable pressure control 38 of any desired type adapted to permit by-passing when predetermined pressure conditions for which the apparatus is desired are obtained.

55 By the use of the unit sections, the apparatus may be initially constructed of such dimensions as to effectively cooperate with

small annealing boxes, and at the same time it may have unit sections added thereto, as required, for increasing its over-all dimensions to permit use of the apparatus with annealing boxes of maximum dimensions. 70

The advantages of the present invention arise from the provision broadly of an apparatus capable of reshaping annealing boxes to restore the same to substantially their original condition. 75

Further advantages arise from the fluid pressure apparatus comprising straightening means and pressure producing means mounted on a common base, which base is also adapted to support the box being straightened. 80

Still further advantages of the invention arise from the provision of a straightening apparatus comprising one member adapted to have unit sections applied thereto or removed therefrom at will, whereby the effective dimensions may be varied as required for boxes of different sizes. 85

I claim:

1. Apparatus for straightening annealing 90 boxes, comprising relatively movable box engaging members adapted to engage opposite points of a box to be straightened, said members having box engaging surfaces of different effective dimensions, one of said members comprising a plurality of removable and replaceable sections adapted to vary the distance between said members, substantially as described. 95

2. Apparatus for straightening annealing 100 boxes, comprising relatively movable box engaging members adapted to engage points in the opposite walls of the box to be straightened, said members having box engaging surfaces of different effective areas, and 105 means for effecting relative movement of said members in both directions, said means comprising spring means for effecting movement of said members in one direction and fluid pressure means for effecting movement 110 in the opposite direction, substantially as described.

3. Apparatus for straightening annealing 115 boxes, comprising relatively movable box engaging members, fluid pressure means for effecting movement of one of said members in one direction, other means for effecting movement of said member in the opposite direction, and a plurality of unit sections 120 detachably carried by one of said members, substantially as described.

4. Straightening apparatus for annealing 125 boxes, comprising a base, a fluid pressure cylinder mounted on said base, a piston movable in the cylinder, a straightening head connected to the piston, a backing up support connected to the cylinder at the end opposite the straightening head, and a plurality of unit sections attachable at will to the backing up support for varying the overall dimensions 130

between the backing up support and the straightening head, substantially as described.

5. Apparatus for straightening annealing boxes comprising a cylinder, a piston in said cylinder, fluid pressure means for actuating the piston in one direction, and a plurality of spring members for returning the piston, each of said spring members comprising a primary and a secondary spring, substantially as described.

6. A straightening apparatus for annealing boxes, comprising a base, a cylindrical casting mounted on said base, a piston movable in said cylinder, fluid pressure means for moving the piston outwardly in said cylinder, a plurality of guide bolts slidably mounted in the cylinder casting, a straightening head connected to said bolts and engaging the piston, said bolts forming guides for the straightening head, and springs surrounding said bolts for returning the piston and the straightening head, substantially as described.

25. 7. A straightening apparatus for annealing boxes, comprising a base, a cylindrical casting mounted on said base, a piston movable in said cylinder, fluid pressure means for moving the piston outwardly in said cylinder, a plurality of guide bolts slidably mounted in the cylinder casting, a straightening head connected to said bolts and engaging the piston, said bolts forming guides for the straightening head, and a primary and secondary spring surrounding each of the bolts for returning the straightening head and the piston, substantially as described.

8. Apparatus for straightening annealing boxes, comprising a base, a cylinder casting carried thereby, a piston movable in said casting, means for producing movement of said piston, and a plurality of unit sections attachable at will to said cylinder casting, substantially as described.

45. 9. Apparatus for straightening annealing boxes, comprising a base, a cylinder casting carried thereby over which the box to be straightened is positioned, a piston movable

in said casting, means for producing movement of said piston, a box engaging member 50 on the piston, a box engaging member on the cylinder casting, and means for increasing the effective overall length between the box engaging members on the cylinder casting and piston, substantially as described. 55

10. Apparatus for straightening annealing boxes, comprising a base arranged to support the box to be straightened, relatively movable box engaging members adapted to engage opposite sides of a box to be straightened when the box is supported on the base, means for securing one of said members to the base, one of said members having a relatively small rounded box engaging surface while the other member has two plane separated portions on 60 opposite sides of the longitudinal axis of the rounded engaging portion, substantially as described.

11. Apparatus for straightening annealing boxes, comprising a base arranged to support the box to be straightened, relatively movable box engaging members adapted to engage opposite sides of a box to be straightened, one of said members being secured to the base and having two separated relatively 70 large box engaging surfaces which form abutments while the other member merely engages the box at one point where it is to be straightened at the side opposite to that engaged by the abutments. 75

12. Apparatus for straightening annealing boxes, comprising a base arranged to support the box to be straightened, relatively movable straightening members adapted to engage points on the opposite walls of the box to be 85 straightened including a piston and a cylinder, means for securing one of said members to the base, means for supplying fluid pressure to said cylinder for moving one member relative to the other, and other means for 90 returning the moved member, substantially as described.

In testimony whereof I have hereunto set my hand.

CARL V. DODGE.
